FOOD DISPLAY CASE

Harold B. Jones, Chicago, Ill., assignor to Leitner
Equipment Company, a corporation of Illinois

Filed May 21, 1962, Ser. No. 70,213

Term of patent 7 years

(Cl. D80—11)

FIGURE 1 is a perspective view taken from the front and one end of a food display case showing my new design, the opposite end being a mirror image of the end shown;

FIG. 2 is a front elevational view thereof, the rear being essentially plain;

FIG. 3 is a cross sectional view of the case taken along the line 3—3 of FIG. 1; and

FIG. 4 is a bottom plan view thereof.

I claim:

The ornamental design for a food display case, substantially as shown and described.
